UNITED STATES PATENT OFFICE.

EDWARD M. AYER, OF THE UNITED STATES ARMY, ASSIGNOR TO NEWTON D. BAKER, SECRETARY OF WAR, TRUSTEE.

CANISTER.

1,388,503.

Specification of Letters Patent. Patented Aug. 23, 1921.

Application filed February 4, 1919. Serial No. 275,024.

(FILED UNDER THE ACT OF MARCH 3, 1883, 22 STAT. L., 625.)

To all whom it may concern:

Be it known that I, EDWARD M. AYER, major Ordnance Dept., United States Army, a citizen of the United States, stationed at 5 Washington, District of Columbia, have invented an Improvement in Canisters, of which the following is a specification.

The invention described herein may be used by the Government, or any of its officers 10 or employees in prosecution of work for the Government, or by any other person in the United States, without payment of any royalty thereon.

One object of my invention is to provide a 15 projectile, or canister for ammunition (specifically, balls), provided with novel means to prevent the customary wedging action which, in other constructions, occurs between the balls, due to the setback of discharge; 20 also, to prevent the usual objectionable scoring of the bore of the gun by the battering of the bore by the use of the ordinary canister; and, also, to save the energy formerly consumed in battering the bore in the usual 25 construction of canisters, thus increasing the longitudinal acceleration and securing a higher muzzle velocity and, consequently, a much greater striking velocity and penetrative effect.

It is another object of the invention to 30 provide a jacket sufficiently strong to normally retain the balls therein but also weak enough to break up at the proper time when fired, thus freeing the balls and allowing 35 them to diverge outwardly.

With these objects in view, the invention resides, broadly considered, in a canister provided with spacing members (specifically, disks), for separating the balls into layers, 40 for the purpose indicated in the first paragraph hereof in combination with a weakened jacket container therefor.

The invention is clearly illustrated in the accompanying drawings, which comprise the 45 following views:

Figure 1 is a central, longitudinal, sectional view of a canister embodying my improvements;

Fig. 2 is a section of the jacket on the line 50 2—2, Fig. 1.

The canister comprises the jacket, 1, which is, preferably, of generally tubular construction and formed, desirably of brass, having the closed tapered nose 2, in which a body of suitable filling and packing material, preferably paraffin, 3 is located, the other end of the canister being spun over a washer or bottom plate 4, as shown at 5.

A designates the balls, within the canister, which are separated into superposed layers 60 by spacing members, in this instance, disks 6.

The jacket 1 of the canister is provided with a plurality of longitudinal slits 7, preferably symmetrically arranged, as shown.

In use, the spacing members 6, as is evident, prevent the usual wedging action, which, in other constructions, takes place between the balls, due to the setback of discharge. The spacing members also prevent the scoring of the bore of a gun, which takes 65 place with canisters not provided with such spacing members, and thus the energy consumed in battering the bore in the usual construction of canisters is saved, thus increasing the longitudinal acceleration, and securing 70 a higher muzzle velocity and, consequently, a much greater striking velocity and penetrative effect.

By the weakened construction, as described, of the jacket 1, it results that the tendency 80 of the jacket is to break up, freeing the balls and permitting them to spread out.

Having thus fully described my invention, what I claim as new and desire to secure by Letters Patent of the United States, is:

A canister for warfare, including a casing closed at its forward end and provided with longitudinal slots, a filler in the forward end of the casing, balls in the casing and arranged in layers, spacing disks between the 90 layers of balls and a closure for the rear end of the casing.

EDWARD M. AYER.
